DESIGN FOR A BOTTLE

Rosalind K. Frame, Yemassee, S. C.

Application January 14, 1948, Serial No. 143,748

Term of patent 14 years

(Cl. D58—8)

To all whom it may concern:

Be it known that I, Rosalind K. Frame, a citizen of the United States and resident of Yemassee, in the county of Beaufort and State of South Carolina, have invented a new, original, and ornamental Design for a Bottle, of which the following is a specification, reference being had to the accompanying drawings, forming a part thereof.

I claim:

The ornamental design for a bottle, as shown.
